(57) **CLAIM**
The ornamental design for a dispenser, as shown and described.

DESCRIPTION

FIG. 1 is a perspective view of a top, front, and left side of an ornamental design for a dispenser;

FIG. 2 is a front elevational view of the dispenser of FIG. 1, the rear elevational view being a mirror image thereof;

FIG. 3 is a left side elevational view of the dispenser of FIG. 1, the right side elevational view being a mirror image thereof;

FIG. 4 is a top plan view of the dispenser of FIG. 1;

FIG. 5 is a bottom plan view of the dispenser of FIG. 1;

FIG. 6 is a perspective view of a top, front, and left side of another ornamental design for a dispenser;

FIG. 7 is a front elevational view of the dispenser of FIG. 6, the rear elevational view being a mirror image thereof;

FIG. 8 is a left side elevational view of the dispenser of FIG. 6, the right side elevational view being a mirror image thereof;

FIG. 9 is a top plan view of the dispenser of FIG. 6; and,

FIG. 10 is a bottom plan view of the dispenser of FIG. 6.

The dash-dash-dash broken lines are for the purpose of illustrating environmental structure and form no part of the claimed design. The dash-dot-dash-dot broken lines on the dispenser of FIGS. 6-10 depict a lower boundary and form no part of the claimed design. The bottom plan views of FIGS. 5 and 10 form no part of the claimed design.
